UNITED STATES PATENT OFFICE.

CLARENCE P. HOLLISTER, OF PITTSFIELD, MASSACHUSETTS, ASSIGNOR TO STILSON MOTOR CAR CO., OF PITTSFIELD, MASSACHUSETTS, A CORPORATION OF MASSACHUSETTS.

INTAKE DEVICE FOR EXPLOSIVE MIXTURES IN VAPOR-ENGINES.

No. 873,372.

Specification of Letters Patent.

Patented Dec. 10, 1907.

Application filed October 4, 1907. Serial No. 395,844.

To all whom it may concern:

Be it known that I, CLARENCE P. HOLLISTER, a citizen of the United States, residing at Pittsfield, in the county of Berkshire and 5 State of Massachusetts, have invented an Improvement in Intake Devices for Explosive Mixtures in Vapor-Engines, of which the following is a specification.

Difficulties have heretofore repeatedly 10 been experienced in multiple cylinder vapor mixture engines from the failure of the vapor mixture intakes and the cylinders supplying the mixture in equal volumes and with equal rapidity, and the object of my invention is 15 to overcome this difficulty.

The device of my invention applies especially to a six cylinder vapor engine and comprises a structure which arranges the six cylinders in three intake groups of two each, all 20 of which latter are supplied with the vapor mixture from a common source. This common source is supplied from a general source divided equally into the common source and the general source is centrally supplied by a 25 single pipe. In this manner the volume of explosive mixture from the single pipe is equally divided and then equally sub-divided and then equally re-sub-divided into the direct intake pipes of all the six cylinders,—all 30 of which is hereinafter more fully expressed.

In the drawing, Figure 1 is a plan and partial central section through the device of my improvement. Fig. 2 is a cross section at the dotted line x, x , of Fig. 1, and Fig. 3 is a 35 cross section through the dotted line y, y , of Fig. 1.

The respective intake pipes to the six cylinders are shown at $a b c d e f$ and $a^1 b^1 c^1 d^1 e^1$ and f^1 are throats that are coupled thereto 40 and which throats merge into the chambers $g h$ and i , and $g^1 h^1$ and i^1 are the three intakes of these three chambers, which are supplied from a common source or continuous chamber k , into the ends of which the intakes g^1 and i^1 open and into the center of which the intake h^1 opens. A general source or chamber l at its respective ends and by intakes l^1 opens into and communicates with the continuous chamber or common source 45 k at points that are substantially midway between the intakes g^1 and h^1 and h^1 and i^1 . A single pipe m supplies the explosive mixture directly into the center of the general source or chamber l .

50 From the illustration and foregoing de-

scription, it will be apparent that the volume of explosive mixture entering through the pipe m into the general source or chamber l is equally divided into the common source or continuous chamber k and is then 60 equally sub-divided at the center and ends of the chamber k and through the three intakes $g^1 h^1$ and i^1 into the chambers $g h$ and i , and is then 65 equally re-sub-divided into the throats $a^1 b^1 c^1 d^1 e^1$ and f^1 connecting with the intake pipes to the respective six cylinders; hence each of the six cylinders will be supplied as nearly as possible with an equal volume of explosive mixture. A proper and perfect working of the said six cylinders is substantially impossible unless an equal volume of explosive mixture is supplied thereto.

I claim as my invention:—

1. A vapor mixture intake device for a six cylinder engine comprising three intake 75 groups of two each, a single intake to each group, a continuous chamber into which the several single intakes open, a general chamber connecting at its respective ends with the said continuous chamber and a single pipe 80 connecting centrally with the general chamber.

2. A vapor mixture intake device for a six cylinder engine comprising an integral structure including three intake groups of two 85 each, a single intake to each group, a continuous chamber into which the several intakes open, a general chamber connecting at its ends and at equally distant places with said continuous chamber and a single pipe 90 connecting centrally with the general chamber.

3. A vapor mixture intake device for a six cylinder engine comprising an integral structure including three intake groups of two 95 each, a single intake to each group, a continuous chamber into which the several intakes open, a general chamber connecting at its ends and at equal distant places with said continuous chamber, a single pipe connecting centrally with the general chamber and pipes extending from each of the two members of the three intake groups to the six companion cylinders of the engine.

Signed by me this 27th day of September 105
1907.

CLARENCE P. HOLLISTER.
